UNITED STATES PATENT OFFICE.

WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK.

DRY CELL.

Application filed July 30, 1923, Serial No. 654,613. Renewed January 12, 1926.

This invention relates to dry cells and more particularly to the construction of dry cells adapted to generate relatively heavy currents.

5 It is the object of the present invention to provide a dry cell of the mentioned type which is efficient in operation and simple to construct.

With this object in view, I provide a construction, in which one of the electrodes, e. g. a zinc can is divided into a plurality of compartments connected in multiple, each compartment constituting substantially a separate cell. The other electrode, e. g. 15 carbon pencil is common to all the cells.

The invention will be more fully understood from the following detailed description of an embodiment thereof and the appended claims.

20 The drawing shows in cross section a dry cell of the carbon-zinc-manganese dioxide type embodying the features of the present invention.

Within a zinc can 1 of the conventional 25 type and size, four bobbins or tablets 2 molded, tamped or pressed of the suitable depolarizing mixture are placed. In assembling the battery, first a disc of paper 3 is placed over the bottom of the can 1. If 30 desired, the bottom of the can may be made of paper or the like, or it may be formed of a separate piece of zinc like the plates or discs 7 to be hereinafter described. Then a bobbin 2 surrounded on the two sides and 35 its bottom by a paper cup 4 is introduced on top of the disc 3. The paper container 4 is preferably coated with paste on the side facing the side wall of the zinc can 1. The paper cup may be introduced first into 40 the can or it may be lowered therein together with the bobbin or tablet 2. The tablets 2 and the cups 4 are provided with a central perforation through which the carbon pencil 5 may pass. On top of the 45 bobbin or tablet 2 which has been lowered into place, a paper disc 6 is placed which is also provided with a central perforation to accommodate the carbon pencil 5. The upper face of the disc 6 is also coated with suitable paste. The containers 4 and discs 50 6 may be made of other absorbent material than paper and serve to absorb the electrolyte introduced in any well known manner.

Now a zinc plate or disc 7 is lowered on top of the disc 6. The zinc plate 7 has 55 a large perforation insuring proper electrical separation from the carbon pencil 5 and is provided with upturned edges 8 by means of which it contacts with the side walls of the zinc can 1 and due to its resiliency will 60 be held in place.

It will be seen therefore that in effect I have a plurality of dry cells the electrodes of which are connected in multiple. Preferably, the tablets 2 are made in substantially 65 the same manner as described in my copending application Serial No. 654,611, filed July 30, 1923.

What I claim is:

1. In a dry cell, a container electrode, a 70 plurality of bobbins of depolarizing mixture within said container, discs of the same material as said electrode between adjacent bobbins and contacting with said electrode, and another electrode projecting through 75 said bobbins.

2. In a dry cell, a zinc container electrode, a plurality of bobbins of depolarizing mixture within said electrode, an absorbent wrapper for each bobbin, zinc discs contacting with said electrode, and separating adjacent bobbins, and a carbon electrode within said zinc container and projecting through said bobbins. 80

3. In a dry cell, a zinc container electrode, a plurality of tablets of depolarizing mixture one above the other within said electrode, a pasted paper container for each tablet surrounding the bottom and side walls thereof, a paper disc covering the top of each tablet, zinc plates separating adjacent tablets, each plate having upturned edges resiliently held by said can, and a carbon electrode within said can projecting through said tablets, paper containers, discs and plates. 85

4. In a dry cell, a container electrode, a plurality of tablets compacted of depolarizing mixture within said container, discs of the same material as said electrode between adjacent tablets and contacting with said electrode, and another electrode projecting through said tablets. 100

In witness whereof, I hereunto subscribe my name this 25th day of July, 1923.

WILLIAM F. HENDRY.
